UNITED STATES PATENT OFFICE.

ARTHUR J. WIDMER, OF WEBSTER GROVES, MISSOURI, ASSIGNOR, BY MESNE ASSIGNMENTS, TO WIDMER ENGINEERING COMPANY, OF ST. LOUIS, MISSOURI, A CORPORATION OF MISSOURI.

CEILING-SUPPORT.

1,243,367.

Specification of Letters Patent.

Patented Oct. 16, 1917.

Application filed May 28, 1916. Serial No. 98,958.

To all whom it may concern:

Be it known that I, ARTHUR J. WIDMER, a citizen of the United States, and a resident of Webster Groves, in the county of St. Louis and State of Missouri, have invented a new and useful Improvement in Ceiling-Supports, of which the following is a specification.

This invention relates particularly to ceilings for ribbed concrete or hollow tile concrete floors, wherein the spaces between the ribs or beneath the tiles are spanned by ceiling boards, the under sides of which are plastered to make a smooth ceiling.

15 The object of the invention is to provide a simple, secure and inexpensive means for supporting the plaster boards from the concrete of the floor. A further object of the invention is to save time and labor in placing the supporting means and in attaching the ceiling boards thereto.

20 The invention consists in a tie or anchor which is driven from above into the form-work for the floor concrete prior to concreting the floor, and which remains securely embedded in the concrete when the forms are removed with its lower end projecting below the concrete ready to tie the ceiling boards to:

25 30 Further details of the invention appear below in connection with the description of the several forms thereof illustrated in the accompanying drawings, and what the invention consists in is more particularly defined in the appended claims.

In the drawings, wherein the same reference characters designate the same parts in the several views,

Figure 1 is a cross-section of a ribbed concrete floor through a rib, showing the floor after the concrete has been poured and prior to the removal of the forms;

Fig. 2 is a similar view of the same floor after the forms have been removed and the ceiling boards have been secured in place;

Fig. 3 is a cross-section of a portion of a rib of a floor similar to that shown in Fig. 2, drawn to a larger scale, showing a modified form of anchor and ceiling board tie;

50 Figs. 4 and 5 are views similar to Fig. 3,

showing other modifications of the anchor and tie;

Fig. 6 is a perspective view of the anchor shown in Fig. 4;

Fig. 7 is a perspective view of the anchor shown in Fig. 5;

Fig. 8 is a perspective view, partly in section, of an anchor similar to those shown in Figs. 2 and 3;

Fig. 9 is a perspective view of another anchor similar to those shown in Figs. 2 and 3;

Fig. 10 is a plan view of a tie plate like those shown in Figs. 2 and 5; and

Fig. 11 is a plan view of a tie plate like those shown in Figs. 3 and 4.

In the construction shown in Figs. 1 and 2, the floor forms 10 are laid on the form-work 11, and anchor ties 12 are driven into the formwork between the forms, after which the concrete 13 is poured, as shown in Fig. 1. The anchor ties have flexible portions 14 at their ends which are driven into the formwork up to the shoulders 15. Upon removing the formwork, the flexible end 75 portions 14 are left projecting below the surface of the concrete.

The ceiling boards 16 are secured in place against the under side of the concrete by means of metal plates 17 which lap under 80 their edges, and which are held up by the anchor ties 12. The depending ends 14 of the anchors project down through holes 18 in the plates 17, and are bent over to hold the plates in place, as shown in Fig. 2. 85

In Fig. 3 another means of securing the ceiling boards 16 is shown. The edges of the ceiling boards rest upon plates 19, which are supported by wires 20 from the projecting ends of the anchors 14. The lower ends 90 of the anchors 14 are bent up to form hooks 21 over which the wires are looped, the lower ends of the wires being passed through slots 22 in the edges of the plates 19 and tied together below the plates. 95

In the form of the invention illustrated in Fig. 4, the anchors 23 are sheet metal strips having slotted holes 24 at their lower ends for the wires 20 which hold up the plates 19 which support the plaster boards 100

16. Each anchor strip 23 has a flange along one edge to stiffen it, the flange terminating short of the point of the anchor strip in a square shoulder 25, as shown in Fig. 6. This shoulder brings up against the form work to position the anchor at the proper depth in the concrete.

The anchor 26 shown in Figs. 5 and 7 is sheet metal like that shown in Figs. 4 and 6, but has two holes 27 one above the other near its point. A nail 28 arranged crosswise through the upper hole in the anchor strip 26 forms a shoulder to engage the form work and position the anchor at the proper depth in the concrete. The plate 17 which supports the plaster boards is held up by a second nail 29 arranged crosswise through the lower hole 27 in the anchor 26.

Figs. 8 and 9 illustrate still further modifications of the invention. Fig. 8 shows an anchor consisting of a wire nail 30 with a sleeve 31 on it to stiffen it above the point. The sleeve is shorter than the nail and forms a spacer for positioning the anchor above the forms to project down below the concrete the desired amount after the forms are removed. Fig. 9 shows an anchor consisting of a wire nail 32 having an enlargement 33 near its point end to form a shoulder for positioning the anchor above the forms in the concrete.

It is evident from the foregoing description that various forms of anchors, ties and plates may be used without departing from the invention; and the invention is not restricted to the forms shown and described.

I claim the following as my invention:

1. The method of constructing a ceiling for a concrete floor which comprises driving an anchor having a pointed lower end into the formwork, embedding the upper end of said anchor in the floor concrete, removing the centering to expose the pointed end of said anchor, and attaching ceiling supporting means to said exposed end.

2. The method of constructing a plastered ceiling for a ribbed concrete floor which comprises driving an anchor having a pointed lower end into the formwork for a rib, embedding the upper end of said anchor in the floor concrete, removing the centering to expose the pointed end of said anchor, attaching ceiling supporting means to said exposed end, and arranging plaster supports for said ceiling against the under side of the rib on each side of said ceiling supporting means and supporting said plaster supports on said means.

3. The method of constructing a ceiling for a concrete floor which comprises driving an anchor having a pointed lower end and a shoulder adjacent to said pointed end into the formwork as far as said shoulder, embedding the upper end of said anchor in the

floor concrete, removing the centering to expose the pointed end of said anchor, and attaching ceiling supporting means to said exposed end.

4. In combination with a concrete floor, a ceiling comprising plaster boards spaced apart at their edges, and means for supporting said plaster board ceiling, said means consisting of spaced anchors partly embedded in said floor, said anchors having integral portions adapted to be driven into the floor forms and projecting below said floor between said plaster boards and having hooks at their lower ends, and metal plates arranged beneath the edges of the plaster boards and held up by said hooks.

5. In combination with a concrete floor and ceiling construction, spaced anchors partly embedded in the under side of said floor, the exposed portion of said anchors having integral portions adapted to be driven into the floor forms and projecting below said floor and having hooks at their lower ends, wires engaging the lower ends of said anchors, and plates sustained by said wires for supporting plaster boards and a plaster ceiling covering said wires and plates.

6. In constructing a concrete floor and ceiling, driving anchors into the forms in rows and subsequently embedding them in concrete, removing the forms to expose the driven ends of said anchors, arranging ceiling boards with gaps between their edges, said gaps being beneath and in alinement with said rows of anchors, the exposed ends of said anchors projecting through said gaps, arranging rows of supporting members for said ceiling boards across said gaps beneath said boards, and fastening said supporting members to the exposed ends of said anchors.

7. A ceiling construction for a concrete floor, said ceiling comprising plaster boards spaced apart in rows, metal plates lapping under the edges of boards of adjacent rows for supporting them at intervals, anchors embedded in the concrete with their lower ends projecting between the plaster boards, and flexible retaining members for sustaining said plates from said anchors, said plaster boards, plates and retaining members being covered by plaster to produce a smooth ceiling.

8. A ceiling for a floor having concrete ribs, said ceiling comprising plaster boards arranged in rows beneath said floor, the edges of the rows being in alinement with said ribs, anchors partly embedded in said ribs and projecting between the edges of said plaster boards, and plates supported by said anchors and projecting under the edges of said plaster boards for supporting them.

1,943,867

9. A ceiling for a floor having concrete ribs, said ceiling comprising plaster boards arranged in rows beneath said floor, the edges of the rows being in alinement with 5 said ribs, anchors partly embedded in said ribs and having hooks on their lower ends projecting between the edges of said plaster

boards, and plates supported by said hooks and projecting under the edges of said plaster boards for supporting them.

Signed at St. Louis, Missouri, this 24th ¹⁰ day of May, 1916.

ARTHUR J. WIDMER.
